UNITED STATES PATENT OFFICE.

JOSEPH OCTAVE BROUSSEAU, OF NORTH HATLEY, QUEBEC, CANADA.

FLUSH-TANK.

No. 909,537.

Specification of Letters Patent.

Patented Jan. 12, 1909.

Application filed May 11, 1908. Serial No. 432,288.

To all whom it may concern:

Be it known that I, JOSEPH OCTAVE BROUSSEAU, a subject of the King of Great Britain, residing at North Hatley, county of Stanstead, in the Province of Quebec, Canada, have invented certain new and useful Improvements in Flush-Tanks; and I do hereby declare that the following is a full, clear, and exact description of the invention, such as will enable others skilled in the art to which it appertains to make and use the same.

The invention to be hereinafter described relates to flushing tanks, and more particularly to a construction and arrangement of the several parts, whereby the siphoning of the tank will be made much more certain than hitherto, and the defective closing of inlet valves and outlet flush pipes and consequent waste of water will be prevented. Broadly speaking, the construction comprises a flush tank box, a feed water inlet to the same, an outlet passage leading from the box, a stand pipe communicating with the outlet, a tube inverted over the upper end of the stand pipe and forming therewith a siphon, a float inclosing the siphon, a valve for closing the feed water inlet, connections between the float and valve, a filling tube for starting the siphon, loose connections between the filling tube and the feed water inlet, and a closure for the flush tank box.

In order to more clearly disclose the construction, operation and use of the invention, reference should be had to the accompanying drawings forming part of the present application.

Throughout the several views of the drawings, like reference characters designate the same parts.

In the drawings: Figure 1 is a vertical cross section on line 1—1 of Fig. 3, looking in the direction of the arrow; Fig. 2 is a vertical cross section on line 2—2 of Fig. 1, looking in the direction of the arrow; Fig. 3 is a horizontal cross section on line 3—3 of Fig. 1, looking in the direction of the arrow, and showing the float and connected mechanisms in plan; Fig. 4 is a vertical cross section on line 4—4 of Fig. 1, looking in the direction of the arrow, and showing the feed water inlet and related parts in sectional detail; Fig. 5 is a vertical cross section on line 5—5 of Fig. 1, looking in the direction of the arrow; Fig. 6 is a section

on line 6—6 of Fig. 5, looking in the direction of the arrow, and showing a rear elevation of the float and connected parts; Fig. 7 is a cross section on line 7—7 of Fig. 6, looking in the direction of the arrow; and, Fig. 8 is an end elevation of the flush tank box.

A box 1, of the general form shown in the drawings, may be used. In this box is mounted the feed valve chamber 2, through which water flows to the interior of the box. At a central point in the box is secured the stand pipe 3, having a contracted delivery passage or opening 4 communicating with the flush pipe 5. The upper end of this stand pipe is provided with a plurality of guide and supporting fingers 6, upon which is seated, in inverted position, a sleeve 7, provided with guide and spacing lugs 8, which, together with the fingers 6, act to hold the sleeve 7 and stand pipe 3 slightly spaced apart to form therebetween an annular chamber 9, which forms the siphon.

In order to insure the action of the siphon, a large open-ended box-like shell or float 10 is provided, which practically fills the entire interior of the box 1 except such part thereof as is taken up by other operating parts to be later described. This float is suspended from the interior of the box by means of the links 11, pivoted respectively to the lower edge of the float and the crank arms 12 of a shaft 13, which passes through the upper end of the box 1, and is provided with a crank handle 14, by which it may be rocked. The links 11 and arms 12 are so proportioned as to hold the float a little above the bottom of the box 1, thus allowing the water to enter beneath the lower edge of the same, and, as the water rises in the box, to form a water seal around the edges of the float. Of course, as the air is compressed in the float by the rising of the water, the float will be gradually lifted. As the float rises, it carries with it the outer arm of a lever 15, to which is connected the valve rod 16, which raises the valve 17 and cuts off the flow of water to the box 1.

In order to allow adjustment of the valve 17 so that the feed of water may be cut off at various points as desired, the upper end of the valve rod 16 is threaded and passed through the sleeve 18, the threaded portion being engaged by a nut 19, which abuts against the upper edge of the sleeve, the sleeve being pivotally connected to the lever

15. In order to prevent the float from becoming locked in its lowermost position as the links 11 and arms 12 become alined, a lug 20 is formed on one of the links and engages the inner face of the back of the tank in time to prevent alinement of the links and arms.

In order to fill the usual form of trap to which the pipe 5 leads, a bent filling tube 21 is provided, which communicates both with the feed water inlet and with the upper end of the stand pipe 3. Communication between the filling tube 21 and the feed water inlet is established by means of the elbow pipe 22. The pipe 22 is of considerably greater diameter than the pipe 21, which is inserted in the lower end thereof. Due to this difference in diameter, there is, of course, an annular passage between the two pipes, through which water flows to the interior of the box 1.

In order to make a perfectly tight joint between the elbow pipe 22 and valve chamber 2, the chamber is bored at its top to receive a tubular bored boss 23, on the elbow pipe, a packing ring 24 of rubber or similar material serving to make the joint water-proof, and screws or similar devices serving to clasp the two parts tightly together.

30. The size and construction of the open-ended shell or float 10 has two particular advantages over all other known constructions for the same purpose. First, because of its size, it acts upon a much greater surface of water for siphoning, and consequently makes siphoning more certain and complete. Second, its unusual size gives it much greater power for operating the feed water valve, and consequently there is no likelihood of the water filling up clear over the float without operating the valve. Also, by constructing the float as an open-ended shell of proportionately large size, it is possible to inclose the stand pipe and siphon tube within it, and so reduce the size of the flush tank box.

The siphoning action of the water through the passage between the stand pipe 3 and sleeve 7 is started by depressing the float 10 and thus forcing the water under the lower edge of the sleeve and up through the passage between the sleeve and the stand pipe. The depression of the float is done by swinging the crank handle 14 toward the dotted line position shown in Fig. 8.

In order to allow the examination of the operating mechanisms, the box 1 is pro-

vided with a rim top or cover 25, having a screened opening 26 for the free passage of air to the interior of the box. 60

It is thought that the operation and use of the invention will be clear from the preceding.

Having thus fully described my invention, what I claim as new, and desire to 65 secure by Letters Patent, is:—

1. In a flushing apparatus of the character described, a tank, a feed water inlet through which water may be delivered to the tank, a siphon in said tank, a valve for 70 controlling the feed of water to the tank, a float mounted within said tank and inclosing the aforesaid siphon, and connections between said float and the aforesaid valve.

2. In a flushing apparatus of the character described, a tank, a feed water inlet through which water may be delivered to the tank, a siphon in said tank, a float suspended within said tank and inclosing the aforesaid siphon, and means for depressing 80 said float to start the operation of the siphon.

3. In a flushing apparatus of the character described, a tank, a feed water inlet through which water may be delivered to 85 the tank, a siphon in said tank, and an open-ended shell float mounted in said tank and adapted to inclose said siphon.

4. In a flushing apparatus of the character described, a tank, a feed water inlet 90 through which water may be delivered to the tank, a siphon in said tank, a valve for controlling the feed of water to the tank, a float mounted within said tank and inclosing the aforesaid siphon, connections between said float and the aforesaid valve, and means for suspending said float above the bottom of the tank. 95

5. In a flushing apparatus of the character described, a tank, a feed water inlet 100 through which water may be delivered to the tank, a siphon in said tank, a float suspended within said tank and inclosing the aforesaid siphon, means for depressing said float to start the operation of the siphon, 105 and means for suspending said float above the bottom of the tank.

In witness whereof I have hereunto set my hand in the presence of two witnesses.

JOSEPH OCTAVE BROUSSEAU.
